UNITED STATES PATENT OFFICE.

CARL J. BALLIETT, OF BUFFALO, NEW YORK, ASSIGNOR TO FOSTER-MILBURN COMPANY, OF BUFFALO, NEW YORK.

DESIGN FOR A PLAQUE OR THERMOMETER-SUPPORT.

57,460.

Specification for Design.

Patented Apr. 5, 1921.

Application filed February 16, 1915. Serial No. 8,637. Term of patent 14 years.

To all whom it may concern:

Be it known that I, CARL J. BALLIETT, a citizen of the United States, residing at Buffalo, in the county of Erie and State of New York, have invented a new, original, and ornamental Design for Plaques or Thermometer-Supports, of which the following is a specification.

The accompanying drawing represents a perspective view of a plaque or thermometer support embodying the design.

The characteristic feature of the design

consists of the main body portion A, the upper part B of which conforms in shape to the figure of a man.

I claim:

The ornamental design for a plaque or thermometer support, as shown and described.
